RADIO SOCKET

Carl L. Knutson, Maywood, Ill., assignor to Cinch
Manufacturing Corporation, Chicago, Ill., a
corporation of Illinois

Application February 23, 1934, Serial No. 712,459

6 Claims. (Cl. 173—328)

My invention aims to provide improvements in socket devices for receiving the projecting contacts of radio tubes and like electrical devices.

In the drawing which illustrates a preferred embodiment of my invention:

Figure 1 is a plan view of one form of socket embodying my invention;

Fig. 2 is an enlarged section taken on the line 2—2 of Figure 1;

Fig. 3 is a section taken on the line 3—3 of Fig. 2, the contact members being omitted;

Fig. 4 is a plan section taken on the line 4—4 of Fig. 2; and

Fig. 5 is a perspective view of a preferred form 15 of rivet structure.

The socket structure illustrated in the annexed drawing is particularly useful for use in connection with radio tubes provided with projecting contact members one of which is located centrally with relation to the others. It should be understood, however, that my improved socket structure may be used with so-called connector plugs and other suitable devices where it is desirable to use a substantially centrally located 25 contact projection together with other surrounding projections.

The particular socket illustrated has a bottom plate 1 (Fig. 2) formed from relatively thin insulating material and provided with a number of 30 apertures 2. In the arrangement illustrated there are five apertures 2, one of which is located in the center of the plate 1 and the others of which are arranged in a circle about the central aperture, as best illustrated in Fig. 4. While 35 yieldable contact members of any suitable construction may be associated with the bottom plate 1, I have shown simple contact members each of which is provided with suitable flange means 3 bearing upon the upper surface of the bottom plate 1 and a tubular contact-receiving portion 4 passing through an aperture 2 (Fig. 2). Each contact is also provided with a soldering lug 5 extending from the yieldable portion 3 for the usual purpose. The socket is also provided 40 with a thin top plate 6 of insulating material having apertures 7 arranged so that they may be aligned with the apertures 2 in the bottom plate 1. In the particular socket structure illustrated a thin spacer plate 8 of insulating material is 45 interposed between the plates 1 and 6 to space those plates apart for purposes which have to do with attaching of the socket to a supporting structure and which have nothing to do with the present invention. This plate 8 also has 50 apertures aligned with the apertures 2 and 7.

As a simple means of securing the plates together and also preventing relative rotation, so that the holes in one plate cannot become misaligned with the holes in the other plate, I have provided a one-piece rivet member which is substantially U-shaped (Figs. 2 and 5) in at least one cross-section thereof. This rivet has a plate portion 9 provided with a central aperture 10 and a pair of leg portions 11—11 extending from opposite sides of the plate portion 9. The rivet 10 is assembled with the socket structure in such a manner that the plate portion 9 overlies the top plate 6 adjacent to the central aperture 7 and has its aperture 10 aligned with the central aperture 7. The leg portions 11—11 pass through 15 all of the insulating plates of the socket structure in notches 12 formed in the sides of the apertures through those plates, as clearly shown in Fig. 4. The free ends of the legs 11—11 which have been previously bifurcated are upset to overlie the 20 lower face of the bottom plate 1 (Fig. 3) thereby securely holding the rivet in place to clamp all of the parts of the socket together between the plate portion 9 of the rivet and the upset ends. It will be readily understood from an inspection 25 of Figs. 2 and 4 how the rivet prevents relative rotation of the insulating plates due to the fact that the legs 11—11 of the rivet fit closely within the notches 12.

My improved structure is particularly useful 30 because in the specific embodiment illustrated it is possible to have a central contact-receiving member in combination with a rivet which does not interfere with the function of the central contact while at the same time providing as simple a construction as has been heretofore possible when the central portion has been set aside entirely for the use of a rivet. My improved structure is simple, easy to assemble and the parts thereof have been reduced to a minimum without 35 affecting the efficiency of the structure.

While I have illustrated and described a preferred embodiment of my invention, I do not wish to be limited thereby because the scope of my invention is best defined by the following claims. 45

I claim:

1. A socket of the class described comprising, in combination, a plurality of superposed apertured plates arranged with their apertures in alignment, contact members assembled between 50 said plates and having portions passing through some of the apertures and with all parts thereof located entirely below the top plate, one of said apertures and contacts being located substantially centrally of the plates with the others 55

arranged in spaced relation about it and rivet means concentrically located with relation to said center contact for securing said plate members together and providing the only means passing through the top plate and holding it against rotation.

2. A socket for use with radio tubes and the like comprising, in combination, a relatively thin plate of insulating material having a number of apertures therethrough, one of which is located substantially centrally of the others, contact members having flange portions and yieldable means extending from the flange portions, each of the apertures having a contact member associated with it so that the yieldable means extends into the aperture, another relatively thin plate of insulating material arranged in superposed relation to the first mentioned plate entirely above the contact members and any parts thereof and having apertures in alignment with the apertures of the said first mentioned plate and rivet means independent of the contact members for securing said plate members together and holding them against relative rotation.

3. A socket for use with radio tubes and the like comprising, in combination, a relatively thin plate of insulating material having a number of apertures therethrough, one of which is located substantially centrally of the others, contact members having flange portions and yieldable means extending from the flange portions, each of the apertures having a contact member associated with it, another relatively thin plate of insulating material arranged in superposed relation to the first mentioned plate and having apertures in alignment with the apertures of the said first mentioned plate, a rivet having a plate portion bearing against the superposed insulating plate and having an aperture in alignment with the central aperture in that plate for access to the contact member associated with the central apertures and leg portions extending from the plate portion of said rivet through the insulating plates in notches at the sides of the central apertures and having their ends upset to secure the parts of the socket together and prevent relative rotation of the insulating plates.

4. A socket for radio tubes and the like comprising, in combination, a bottom plate having a central aperture therethrough and a number of similar apertures circumferentially arranged about the central aperture, a contact member associated with each of said apertures and provided with flange means bearing against the upper surface of the bottom plate and yieldable contact-receiving portions passing through the apertures, a top plate superposed upon the bottom plate and having apertures therethrough in alignment with the apertures in the bottom plate and a single U-shaped rivet having an apertured portion bearing against the upper surface of the top plate in alignment with the central aperture therein and having its leg portions passing through both plates with the free ends thereof upset against the bottom plate, said single rivet providing the only means securing the parts of the installation in predetermined assembled relation.

5. In a socket device for use with a part having a male electrical contact member, at least two superposed apertured insulating plates arranged with the aperture of one plate in alignment with the aperture in another, a female electrical contact member assembled with a portion between said plates and another portion extending through one of said plates, and a one-piece generally U-shaped rivet arranged concentrically with said apertures and having the leg portions of the U extending through said plates and the free ends upset to hold the parts of the device in assembly.

6. In a socket device for use with a part having a male electrical contact member, said socket device including a pair of insulating plates, a female electrical contact member assembled as a part of the socket device to receive the male contact member and a U-shaped assembly rivet having an apertured portion in alignment with the female contact member and having its leg portions spanning the female contact member with the free ends of the leg portions upset to hold the plates of the socket device in assembled relation.

CARL L. KNUTSON.
